(57) **CLAIM**

I claim the ornamental design for a mesh sponge with a pocket, as shown and described.

DESCRIPTION

FIG. 1 is a front isometric view of a first embodiment of a mesh sponge with a pocket.

FIG. 2 is a detail view of a portion of the mesh sponge with a pocket of FIG. 1 depicting multiple layers of mesh material.

FIG. 3 is a front elevation view of the mesh sponge with a pocket of FIG. 1.

FIG. 4 is a rear elevation view of the mesh sponge with a pocket of FIG. 1.

FIG. 5 is a right elevation view of the mesh sponge with a pocket of FIG. 1.

FIG. 6 is a left elevation view of the mesh sponge with a pocket of FIG. 1.

FIG. 7 is a top plan view of the mesh sponge with a pocket of FIG. 1.

FIG. 8 is a bottom plan view of the mesh sponge with a pocket of FIG. 1.

FIG. 9 is a front isometric view of a second embodiment of a mesh sponge with a pocket.

FIG. 10 is a detail view of a portion of the mesh sponge with a pocket of FIG. 9 depicting multiple layers of mesh material.

FIG. 11 is a front elevation view of the mesh sponge with a pocket of FIG. 9.

FIG. 12 is a rear elevation view of the mesh sponge with a pocket of FIG. 9.

FIG. 13 is a right elevation view of the mesh sponge with a pocket of FIG. 9.

FIG. 14 is a left elevation view of the mesh sponge with a pocket of FIG. 9.

FIG. 15 is a top plan view of the mesh sponge with a pocket of FIG. 9; and,

FIG. 16 is a bottom plan view of the mesh sponge with a pocket of FIG. 9.

The broken lines shown in FIGS. 9 and 11-15 are for illustrative purposes only and are not part of the claimed design.
